UNITED STATES PATENT OFFICE.

JOHN B. WHITNEY, OF NEW YORK, N. Y.

DESIGN FOR BELL-PULLS.

Specification forming part of Design No. 6,557, dated April 1, 1873; application filed January 6, 1873.

To all whom it may concern:

Be it known that I, JOHN B. WHITNEY, of the city, county, and State of New York, have invented a new and original Design for a Bell-Pull, of which the following is a specification:

The accompanying engraving fully represents my new design.

This invention relates to a new ornamentation for a plate, lever, and knob of a bell-pull. The circular plate contains in the middle an antique head with a helmet on, around which a circle of radiating lines is arranged. The same is surrounded by a border having a floral design, around which another border with undulating ornament is formed. The lever or

handle of the bell-pull contains, as ornamentation, a fantastic branch with leaves and ten-drills, while the knob has an ornament similar to a letter X on its face.

I claim as my invention—

1. The design for the circular plate of a bell-pull, as shown.
2. The design for the handle or lever of a bell-pull, as shown.
3. The design for the knob of a bell-pull, as shown.

JOHN B. WHITNEY.
